UNITED STATES PATENT OFFICE.

HEINRICH KLOPSTOCK, OF AUSSIG, CZECHOSLOVAKIA.

PROCESS FOR THE ELECTROLYSIS OF ALKALI CHLORIDES.

Application filed May 25, 1925. Serial No. 32,778.

To all whom it may concern:

Be it known that I, HEINRICH KLOPSTOCK, a citizen of the Republic of Czechoslovakia, residing at Ohnsorgstrasse 17, Aussig, in the Republic of Czechoslovakia, have invented certain new and useful Improvements in Processes for the Electrolysis of Alkali Chlorides (for which I have filed a patent application in Germany on 21st May, 1924), 10 of which the following is a specification.

It is well known that, if the electrolysis of alkali chlorides by the so-called quicksilver process is to be carried out in a favourable manner, one of the chief conditions to 15 be observed is that the surface of the quicksilver be kept right.

Nevertheless, in this process, when the quicksilver in the amalgam decomposition cell is returned into the amalgam-formation cell by means of mechanical devices, such as bucket-wheels, pumps or the like, a troublesome friability of the quicksilver often occurs, which is presumably due to oxidation of the residue of alkali metal in it. 25

It has now been found that this drawback, which occurs to a particularly great extent in the electrolysis of potassium chloride, can be obviated in a simple manner by effecting the transference of the quicksilver from the amalgam decomposition cell to the amalgam-formation cell in the presence of a suitable air-excluding medium, for example liquids such as water, diluted alkali lyes or alkali chloride solutions. Or, similarly successful result may be obtained by effecting the transference of the quicksilver in the presence of an inert gaseous atmosphere, for example, in the presence of hydrogen or nitrogen. It is advantageous in many cases 40 to effect the transference of the quicksilver under a combined gas and liquid seal.

In this manner the undesirable friability of the quicksilver may be avoided not only in the electrolysis of sodium chloride but also in the electrolysis of potassium chloride. 45

Any suitable apparatus for carrying out the process may be employed. A preferred form of apparatus is illustrated by way of example, in the accompanying drawing.

In the drawing, which illustrates diagrammatically a sectional elevation through the apparatus, 1 is a container from which

the liquid metal has to be continually lifted into a higher container 2. The layer of liquid metal is indicated by 3 and the layer 55 of protecting liquid above it by 4. A baffle 5 is provided for preventing the protecting liquid from taking part in the circulation. The actual transfer device 6 consists of a worm which is rotated by means of the shaft 60 7 which is provided with a closure against the liquid. A plate 8, the lower surface of which is curved, is directly fitted to the transfer device 6 and at such a height that its outermost edge coincides with the highest 65 level of the liquid metal to be raised. The result is thereby obtained that the transferred liquid metal, in spite of its upward movement due to the action of worm, cannot be driven through the covering liquid. 70

The invention is not limited to the apparatus illustrated as, obviously, any other suitable means for transferring the quicksilver from the one cell to the other in the presence of an air-excluding medium might 75 be employed.

I claim.

1. In processes for the electrolysis of alkali chlorides by the so-called quicksilver process involving a transfer of the quicksilver from the amalgam decomposition cell to the amalgam-formation cell by a fluid propelling device, the step which consists in protecting the quicksilver throughout its transfer by means of an air-excluding fluid. 85

2. In processes for the electrolysis of alkali chlorides by the so-called quicksilver process involving a transfer of the quicksilver from the amalgam decomposition cell to the amalgam-formation cell by a fluid propelling device, the step which consists in protecting the quicksilver throughout its transfer by means of an air-excluding liquid. 90

3. In processes for the electrolysis of alkali chlorides by the so-called quicksilver process involving a transfer of the quicksilver from the amalgam decomposition cell to the amalgam-formation cell by a fluid propelling device, the step which consists in protecting the quicksilver throughout its transfer by means 95 of water. 100

4. In processes for the electrolysis of alkali chlorides by the so-called quicksilver process involving a transfer of the quicksilver from

the amalgam decomposition cell to the amalgam-formation cell by a fluid propelling device, the step which consists in protecting the quicksilver throughout its transfer by means of a liquid and an inert gas.

5. In processes for the electrolysis of alkali chlorides by the so-called quicksilver process

involving a transfer of the quicksilver from the amalgam decomposition cell to the amalgam-formation cell by a fluid propelling device, the step which consists in protecting the quicksilver throughout its transfer by means of water and hydrogen.

DR. HEINRICH KLOPSTOCK.
